UNITED STATES PATENT OFFICE.

GEORGE AUGUSTUS SCOTT, OF NEW YORK, N. Y.

DESIGN FOR A CURLING AND CRIMPING COMB.

SPECIFICATION forming part of Design No. 18,995, dated April 2, 1889.

Application filed February 27, 1889. Serial No. 301,428. Term of patent 7 years.

To all whom it may concern:

Be it known that J. GEORGE AUGUSTUS SCOTT, a citizen of the United States, residing in the city of New York, county and State of New York, have invented and produced a new and original Design for a Curling and Crimping Comb, of which the following is a specification, reference being had to the accompanying drawings, forming part thereof.

10 Figure 1 is a side view of my new crimper, showing the design thereof; Fig. 2, a top view of the same.

15 The leading peculiarities of this design are in the configuration of a curling-comb united to a button-hook by an intermediate handle of wood. The handle is round and elliptically elongated, with a swell in the central section

tapering gradually toward each end. It is also grooved circumferentially, but plain at the ends, conforming to the shanks of the 20 comb and button-hook sections at the points of junction *a b*.

What I claim as my invention is—

A design for a curling and crimping comb exhibiting a round handle circumferentially 25 corrugated and tapering from its center to the ends, to one of which is secured a comb, to the other a button-hook, substantially as shown.

GEORGE AUGUSTUS SCOTT.
